COMBINATION ELECTRICAL CONTROL
ASSEMBLY

Newton C. Schellenger, El Paso, Tex., assignor to
Chicago Telephone Supply Company, Elkhart,
Ind., a corporation of Indiana

Application February 2, 1939, Serial No. 254,318

7 Claims. (Cl. 201—48)

This invention relates to a new and improved combination electrical control assembly and more particularly to such an assembly where the units are closely associated and connected for joint operation.

In one specific form the assembly comprises a variable resistance as one unit and an associated switch as the second unit. Assemblies of this character are in wide general use in radio receivers and transmitters, public address systems, test apparatus and the like. In many applications of such units the switch and variable resistance are connected in different parts of the circuits involved and any electrostatic, electromagnetic or capacity coupling between the parts is undesirable. Specific examples are where such combination assemblies are used in radios or audio amplifiers with the switch controlling the alternating current input to the apparatus and the variable resistance connected as a volume control in some portion of the circuit after which there is substantial audio amplification. In such cases an alternating current hum from the switch may be picked up by the variable resistance and amplified to such an extent as to be highly objectionable.

Combined assemblies have in the past been made with a metallic shield located between the units and with a switch operating cam extending through an opening in the shield. In such devices, where the cam is not connected into either electrical circuit and where the current carrying portions of the switch are located to one side of the opening, sufficient shielding effect is afforded for many applications of such devices.

With the more compact assembly of parts now customary in the radio and other fields using devices of this character, parts are so closely placed that very efficient shielding is often required. It is often necessary not only to shield the switch from the associated control unit but also to shield the switch and sometimes the second unit from adjacent parts such as unshielded tubes or coils.

It is an object of the present invention to provide a new and improved combination electrical control assembly.

It is an additional object to provide an assembly of this character where a plurality of units are connected for joint operation.

It is also an object to provide such an assembly in which there is effective shielding between units of the assembly by a fixed imperforate shield member interposed therebetween.

It is a further object to provide an assembly

which is compact and simple in design and construction and adapted for commercial production.

Other and further objects will appear as the description proceeds.

I have shown certain preferred embodiments of my invention in the accompanying drawing, in which—

Figure 1 is an elevation of the combination control with portions broken away;

Figure 2 is a section taken on line 2—2 of Figure 1;

Figure 3 is a perspective view of the operating member; and

Figure 4 is a plan view, on a reduced scale, showing the switch cover.

The combination electrical control shown, comprises a first unit having a base 11 formed of insulating material and having a metallic housing 12 secured to the base and enclosing the mechanism of the unit. In the form of construction shown, this unit is a variable resistance similar to that shown in my prior application, Serial No. 218,062, filed July 8, 1938. The unit includes a metallic thimble 13 secured to the base 11 and a rotary shaft 14 extending through the thimble 13 and through the base into the housing 12. This shaft carries an insulating drive plate 15 and a metallic stop plate 16 which are keyed to the shaft and rotated therewith.

The details of construction of the variable resistance unit form no part of the present invention. It may be briefly stated that the unit includes a movable contact member 17 driven by the arm 15 and engaging a resistance strip not shown. The contact member 17 also makes contact with the collector ring 18 which is connected to one of the terminals 19. The other terminal 20 may be connected to an end of the resistance strip. The device may include a third terminal connected to the offset end of the resistance strip which terminal would be in the rear of terminal 20, as seen in Figure 1. It is to be noted that the base 11 is generally circular in shape, but is provided with an extended portion 21 to which the terminal lugs 19 and 20 are secured. The metallic housing 12 carries around the inner side of its cylindrical face an insulation strip 22 which insulates the housing from the portions of the device therein, and the insulating strip also serves to close cut-away portions in the metallic housing adjacent the base. The metallic stop member 16 has an upturned portion 23 terminating in a stop member

24 adapted to engage either side of the stop 25 formed by pressing in a portion of the housing 12. This stop member 16 is also provided with an upturned lug 26 adapted to transiently engage the operating member 27 for driving the second unit.

In the form of construction shown, the second unit comprises a switch substantially similar to that shown in my copending application, Serial No. 83,963, filed June 6, 1936, and will not be described in detail herein. The switch is supported on an insulating base 28 which in turn is supported by a metallic housing member 29 secured to the end wall 30 of the housing 12 of the first unit. As best shown in Figure 4, the member 29 in addition to the substantially cylindrical wall, comprises an outer face portion 33 which overlies the greater portion of the insulating switch base 28 and is cut away to give clearance to the terminals 37 and 38. Thus the switch with the exception of the terminals, is enclosed within a metallic shield.

The member 29 is secured in place as shown by means of the lugs 31 which pass through slots in the wall 30 and are clinched over against the under surface of the wall. The ends of the lugs 31 are turned inwardly when clinched so that they completely close any portions of the slots in the end wall 30 lying within the switch housing wall and thus insure an imperforate fixed metallic wall between the two units.

The switch of the second unit comprises a pivot 32 which is secured through the base 28 and also through the outer face portion 33 of the metallic wall member 29. The switch pivot is grounded by this connection to the wall 29. Upon this pivot 32 are carried the switch arm 34 and also the operating member 27. The spring 35 is connected between the operating member 27 and the switch arm 34 and serves to drive the switch arm upon oscillation of the operating member 27 across the dead center, giving what is called a toggle or snap action to the switch. The switch arm 34 drives a U-shaped contact member 36 into and out of engagement with spaced fixed contacts 52 and 53 connected to the solder lug terminals 37 and 38. The operating member 27 is provided upon the supporting leg 39 with the U-shaped portion 40 which provides a double bearing for the member 27 upon the pivot 32. The opposite arm 41 is provided with an enlarged cut-away portion 42 which forms the spaced horns 43 and 44. It will be noted that the cut-away portion 42 is opposite the pivot 32 and this portion is designed to afford clearance for a riveting tool used to upset the end 45 of the pivot 32.

As shown in Figure 1, the portion 39 of the operating member extends outwardly through an opening 46 formed in the housing wall 29 of the second unit or switch member. The portion 41 of the operating member extends inwardly through an opening 47 formed in the lateral wall of the first unit housing 12. The switch arm 34 of the second unit is preferably formed of insulating material so that the operating member 27 is not connected in or to the electrical circuit passing through the switch. As clearly shown in Figure 1, the operating member 27 extends outwardly laterally of the two units at a point above the extended portion 21 of the base 11. It also extends out only a comparatively short distance so that it does not engage the connecting lugs 19 and 20.

It will be seen that my improved construction

comprises a structure with the two control units enclosed in metal walls and with an imperforate wall located between the units. Adjacent slots are provided in the lateral walls of the unit housings for passage of means for jointly operating the devices. This joint operating means is formed of metal and is grounded by connection to the housings so that it in itself serves as an additional shield. The parts are so designed that the slots in the unit walls are small and are to a large extent closed by the joint operating means. Thus this means plays an important part in the total shielding effect. In certain forms of construction as shown, in order to reduce the overall size of the unit, the joint operating means may be located adjacent the terminals of the variable resistance unit. In such cases this means is effective in shielding the terminals of the variable resistance from the switch.

In operation of the device the resistance between the end terminals and the center terminal 19 connected to the movable contact in the resistance unit or first unit, is varied by rotating the shaft 14, and consequently rotating the movable contact 17. At the end of the movement in which the parts are shown, the second unit or switch is in the "off" position.

Referring now to Figure 2, if the shaft 14 as seen in that figure is rotated in a clockwise direction, the lug 26 will be pivoted in the same direction and will engage the horn 43 of the member 27. It will rotate the member 27 in the counterclockwise direction about its pivot 32. As soon as the spring 35 passes the dead center, the switch is snapped to "on" position by the force stored in this spring. As the shaft 14 is rotated further, the lug 26 may pass freely away from the member 27. When the shaft 14 is rotated toward its limit in the counterclockwise direction, the lug 26 will engage the horn 44 of the member 27 and will move that member in the clockwise direction to open the switch.

It will be apparent that my construction affords a complete imperforate metallic shield between the current-carrying portions of the first unit and the current-carrying portions of the second unit. The metallic wall 29 of the second unit and the metallic housing 12 of the first unit are connected together electrically and mechanically, and both of these members may be grounded in any suitable manner. The usual method of grounding is by connecting the housing 12 to the thimble 13 which is in normal use mounted upon a metallic chassis which serves as ground. In the form of construction shown, the grounding plate 48 is shown between the base 11 and the metal washer 54 which is secured to the thimble 13 and this plate has an upturned portion 49 through which passes one of the securing lugs 50 for the housing 12. This lug is bent over against the under face of the plate 48 and affords an effective grounding connection.

The member 27 is not connected in or to the electrical circuit in either unit, and this operating member is, therefore, what is called "cold." It is grounded at all times through the pivot 32 which is directly connected to the portion 33 of the switch housing wall 29. It effects no transfer of energy from one unit to the other and therefore in no way affects the complete shielding between the units afforded by the end wall 30 of the housing 12. The con-

nection between the units is simple and requires no more parts than connections accomplished in the prior art by operating members or cams which pass through the end walls of the adjacent units. While the shielding afforded with the switch cam extending directly through perforations in the metal end wall is adequate for certain uses and requirements, it does not afford as completely effective shielding as that given by the imperforate shielding wall of the present construction. This connection does not increase the effective size of the units since it extends out of the housings above the extended portion 21 of the base, which is provided to carry the terminals clear of the housing for connection to the wires leading to other portions of the circuit.

Attention is directed to the fact that the stop carrying arm 23 and its stop portion 24 travel in a plane located between the end wall 39 and the leg 41 of the operating member 27. By virtue of this structural relationship, the stop arm 23 may be directed outwardly far enough to have its outer end traverse an arc close to the side wall of the housing 12 from which the stationary stop 25 projects. Hence, the stop 25 can be quite short in a radial direction, which is desirable as it is thus stronger and easier to fabricate.

While I have shown certain preferred forms of construction, it will be apparent that the assembly is capable of modification and change to meet varying conditions and requirements and I contemplate such variations as come within the spirit and scope of the appended claims.

I claim:

1. In combination, two electrical control units arranged in tandem and each having a substantially cylindrical housing with a metal side wall, a substantially unbroken metal partition wall separating and shielding the units from each other, a rotary shaft substantially coaxial with and projecting from one unit and operable to actuate the instrumentalities thereof, the side walls of the housings having openings, an oscillatable operating member for the other unit pivoted within the housing thereof and extending out through the opening in its side wall around the partition wall and back in through the opening in the side wall of the first named unit, and means in the first named unit driven by its shaft for actuating said operating member.

2. In combination, an electric snap switch of the type having a movable contactor driven from one position to the other by a spring toggle device, a substantially cup-shaped housing for the switch having a metal side wall provided with an opening, an operating member for the toggle device pivoted within the housing of the switch and having a U-shaped part projecting laterally through the opening in the housing side wall with its inner leg in said opening and the outer leg spaced from the plane of the open end of said cup-shaped housing, an electrical control unit of the type having rotary elements driven by a rotary shaft, a substantially cup-shaped housing for said control unit having a substantially unbroken metal end wall and having an opening in its side wall, and means holding the switch and control unit assembled with the switch housing having its open end closed by the metal end wall of the control unit housing so that said end wall separates and shields the switch from the control unit and is straddled by the legs of the U-shaped operating member with the outer leg

entering the control unit housing through the opening therein to be actuatable by the rotary elements of the unit.

3. In combination, an electric snap switch, a switch housing having a metal side wall with an opening therein, an operating member for the snap switch consisting of a substantially U-shaped metal stamping, a pivot post in the switch housing of the switch grounded to the metal side wall and having the operating member pivoted thereon so that the operating member is also grounded, the inner leg of the U-shaped operating member extending laterally out through the opening in the side wall of the switch housing so that its outer leg extends inwardly toward the center of the switch, an electrical control unit of the type having rotary elements driven by a rotary shaft, a housing for said control unit having a metal side wall provided with an opening, a substantially unbroken metal partition wall providing an end wall common to both housings and separating and shielding the switch from the control unit, said partition wall being interposed between the legs of the U-shaped operating member and the outer leg of the operating member entering the housing of the control unit through the opening in its side wall, means rotatable with the rotary elements of the control unit adapted to have transient engagement with the outer leg of the U-shaped operating member inside the control unit housing, a stop arm rotatable with said rotary elements of the control unit moving in a plane lying between said common end wall of the housings and said outer leg of the operating member, and a stationary stop on the side wall of the control unit housing engageable by said stop arm.

4. In combination, two electrical control units, a housing for each unit having a substantially cylindrical side wall, a substantially unbroken metal partition wall connected with the side walls of the two housings so as to provide a common end wall for the two housings and an unbroken electrostatic shield between them, the side walls having openings adjacent to each other at opposite sides of the partition wall, a U-shaped operating member straddling the common end wall with the legs thereof passing through the side wall openings and its closed end outside the housings, a pivoted support for the U-shaped operating member, a driving connection between the operating member and the instrumentalities of one unit, a rotary shaft for driving the instrumentalities of the other unit, and means driven by the shaft and operable on the leg of the operating member inside the housing of the second designated unit for actuating the same so that both units are controlled from the one rotary shaft.

5. In a combined volume control and switch of the type intended for use with radio apparatus, separate housings for the volume control unit and switch unit, one of said housings having a substantially unbroken metal end wall, means for holding the housings assembled so that the two units are arranged in tandem with said substantially unbroken metal end wall forming an electrostatic shield therebetween, a base for one of said units constituting part of its housing and disposed substantially parallel to said end wall, a lateral extension on said base providing a terminal support, the housings of the two units having side walls, each of which has an opening adjacent to said lateral extension of the base, a common operating shaft for the two

units entering the housing of one of the units, and an actuator for the other unit operable by the shaft, said actuator comprising a motion transmitting member having spaced arms, each entering one of the housings through its side wall opening with its exposed portion overlying the lateral base extension.

6. In a combination radio control, a first unit having a base, a substantially cup-shaped housing for said unit having its open end closed by the base and having a substantially unbroken metal end wall overlying the base, said housing having an opening in its side wall, a second unit, a substantially cup-shaped housing for said second unit having at least its side wall of metal, a pivoted actuator for the instrumentalities of the second unit, the metal side wall of the housing for the second unit having an opening, means for holding the two units assembled with the second unit mounted on the outer face of the substantially unbroken metal end wall of the first unit, means on the pivoted actuator projecting out through the opening in the side wall of the housing of the second unit and back into the housing of the first unit through the opening in its side wall, a common operating shaft for the two units entering the housing of the first unit through the base to drive the movable elements of the first unit, and means inside the housing of the first unit for transmitting driving force from the shaft to said means on the pivoted member.

7. In combination, an electric snap switch unit of the type wherein a movable contactor is

snapped from one position to the other by a spring toggle device, a substantially cup-shaped switch housing having an opening in its side wall, a base in the bottom of the cup-shaped housing, a pivot post carried by the base near that portion of the side wall having the opening, an operating member for the spring toggle device of the snap switch unit, said operating member being pivoted on said post and having a U-shaped portion extending laterally from the post with its inner leg disposed in said opening and its outer leg directed back over the pivot post but spaced therefrom and from the plane of the open end of the housing, a substantially unbroken metal wall closing the open end of the cup-shaped housing and connected with the side wall thereof to provide a shielding barrier, said wall being straddled by the legs of the U-shaped portion of the operating member so that the outer leg thereof overlies the wall, an electrical control unit operable in conjunction with the snap switch, means holding said electrical control unit assembled with the snap switch with the two units arranged in tandem and the control unit disposed on the exterior of said substantially unbroken metal wall and wholly within the confines of its peripheral edge, said control unit having rotatable instrumentalities, means on said rotatable instrumentalities adapted to have driving engagement with said outer leg of the U-shaped portion of the operating member, and a manually rotatable operating member for the rotatable instrumentalities of the control unit.

NEWTON C. SCHELLENGER.
